11 Claims. (Cl. 338—276)

ABSTRACT OF THE DISCLOSURE

A resistor comprising an elongate core bearing an elongate coating of resistive material thereon, and terminal means comprising a conductive tubular terminal member and a conductor having two end portions connected by a bight, the bight extending around the core in contact with the resistive material and drawn tightly under tension against the resistive material, and the end portions of the conductor secured under tension in the tubular terminal member and electrically connected to the latter.

The invention herein disclosed pertains to terminal connections in variable resistors, and more particularly to improvements in terminal connections for resistance elements of the composition type whereby accuracy of determining an electrical end of an element is improved and permanency, reliability and conductivity of the termination are improved.

Various types of terminal structures have been devised with a view toward effecting accurate end-points and low-resistance terminations for variable resistors in the composition-element (molded, cermet, or metal-film) class. A typical example is noted in U.S. patent to Schellenger, No. 2,118,112, in which special grooves are made and filled with material offering good conductivity between the body of the resistive composition element and metallic terminals. Also the problem is discussed in U.S. Patent No. 2,736,783. While the same problem is presented in the case of wire-wound potentiometer resistance elements (as indicated in U.S. Patent No. 2,783,343), the solution is there much simplified by the availability of an end boundary furnished by a selected turn of wire; whereas there is no such boundary available in an arcuate or helical composition-type resistance element. By the present invention there are provided means and method for producing a very distinct and effective termination for that type of resistance element in which an insulated curved or helical wire-like core or mandrel carries adherent thereto an elongate curved mass of resistive composition. The electrical end of the element, at which the resistance exhibited between the potentiometer wiper or contact and the adjacent terminal is desirably zero, is very sharply defined and is such that as the wiper or contact approaches it the exhibited resistance reaches zero value at the same mechanical position on every cycle of operation. Such accurate definition of the electrical ends of the elements is of great importance in precision potentiometers, such as those employed in servo systems.

The invention accomplishes the aforementioned results by providing a distinct sharply-defined fixed metal-to-composition boundary which is disposed at right angles to the path of the wiper, and a highly conductive (substantially zero-resistance) path from the boundary to the potentiometer terminal. The resistance element proper, of the character of an applied resistive coating or layer extending along and firmly adherent to an elongate insulative wire-like core or mandrel along one "side" or longitudinally-extending zone of the mandrel, is transversely crossed by a conductive member that preferably is in the form of a thin flat ribbon of conductive metal such as nickel or silver alloy, the conductive member being drawn

2

under tension tightly into contact with the resistive material and there maintained under tension. Thus one edge of the conductive member defines a line-like boundary extending transversely across the resistive coating, at which boundary the resistance of the electrical path to the terminal abruptly drops substantially to zero value. The preferably flat ribbon-like conductive member is placed under tension, as by being drawn around the resistance element and drawn into contact with a tubular terminal and while drawn taut is fusion-united to the terminal, whereby a highly-conductive low-resistance connection of the element boundary to the terminal is effected. To aid in insuring permanency of the contact or connection between the conductive member and the resistive material, conductive adhesive is preferably applied over at least a portion of the conductive member and adjacent resistive material adjacent the edge of the conductor distant from the noted boundary; and the tubular terminal is filled with molten metal, such as solder, which upon cooling serves to place the conductive member under high permanent tension. Initial fusion-uniting of end portions of the tensioned conductive ribbon to the terminal is conveniently effected by spot-welding, whereby to facilitate application of solder as will be explained.

The preceding brief general description of the invention makes it evident that a principal object of the invention is to provide improvements in variable resistor composition resistance-element terminations.

Another object of the invention is to provide improved means and methods for electrically terminating composition-type resistance elements in variable resistors.

An additional object of the invention is to provide improvements in demarking the electrical boundary between an end of a composition resistance element and a variable resistor terminal.

Other objects or advantages of the invention will hereinafter be stated or made evident in the appended claims and following description of an exemplary variable resistor incorporating a preferred embodiment of termination according to the invention, the description containing references to the accompanying drawings forming part of this specification. In the drawings:

FIGURE 1 is a pictorial representation, to an arbitrary scale, of a typical variable resistor as modified to incorporate a resistance-element termination according to the invention;

FIGURE 2 is a view in cross-section of parts of the resistor depicted in FIGURE 1, to enlarge scale, the section being taken on a plane and in the direction indicated by the arrows and broken line 2—2 in FIGURE 1, certain conventional parts having been removed and portions broken away for convenience in illustration of pertinent details of the invention;

FIGURE 3 is a sectional view, to enlarged scale, of structure depicted in part in FIGURES 1 and 2, taken as indicated by broken line 3—3 in FIGURE 2, with a portion broken away; and

FIGURE 4 is a fragmentary sectional view, taken as indicated by broken line 4—4 in FIGURE 2, to a different scale and with a portion broken away, showing relationships of parts according to the invention.

Referring first to FIGURE 1, the exemplary variable resistor, selected for convenience in this instance to be in the form of a multi-turn helical-element precision potentiometer, is denoted generally by ordinal 10. The resistor comprises a housing of any desired configuration, here shown as a generally cylindrical shell or barrel 12 having end caps 14 and 16 through the latter one of which the conventional rotary adjusting shaft 18 extends. Accessible inside the barrel of the housing for connection to ends of a resistance element, and extending outwardly through apertures formed in the barrel, are first and second prefer-

ably tubular or hollow terminals 20 and 22, respectively. Similarly, a third terminal 24, which may be solid or like the others, is provided to which electrical connection from the potentiometer wiper contact is provided in manner and by means well known in the art.

Disposed against the inner wall surface of the barrel 12 and preferably seated in a curved or helical groove formed in that wall, is an insulated resistance-element core or mandrel 30 of helical form or configuration, as may be usual in helical-element precision potentiometers as depicted for example in U.S. Patents Nos. 2,815,422; 2,850,606; 2,866,053; and 2,866,056. Preferably, but not necessarily, the core or mandrel is of circular or round cross-section. Carried by the insulated mandrel and extending along an elongate surface zone or area of the exposed inner surface thereof is a composition resistance element proper 30e, preferably applied and formed and of characteristics disclosed in application for Letters Patent of the present inventor, Ser. No. 468,508, filed of even date herewith and entitled Variable Resistor Element. The element proper, or resistive component of the resistor, is a hardened-in-situ coating or strip of resistive composition that preferably is under some degree of compressive stress, as described in the aforementioned application, to which reference may be had for details. The core or mandrel is, in usual manner, cut from a long helical coil prior to installation in the housing, and is cut sufficiently long to provide the full extent of coating for wiping by the potentiometer contact, plus extents sufficient to provide for effective terminations or terminal connections, as will presently be made evident. For example, a mandrel of 355° extent might be severed for an element for a single-turn rotary precision potentiometer, or an extent of 3630° $\pm 10^\circ$ might be severed for the helical element of a ten-turn rotary precision variable resistor, as will be evident to those skilled in the art.

Since the termination structures are or may be substantially identical at opposite ends of the curved or helical element, only that at terminal 20 of the exemplary ten-turn variable resistor will be described in detail. As indicated in FIGURES 2 and 3, terminal 20 is a conductive, shaped, preferably tubular or longitudinally slotted body having a shoulder or flange 20f fitted against a complementary surface provided on the exterior of insulative barrel 12, and having further an inner portion 20i firmly affixed in a hole formed through the barrel wall. The terminal is firmly affixed to the barrel, as by a press fit aided if desirable by adhesive, in a fashion known in the art. The exterior end of the terminal is preferably provided with a head 20h as may be usual to facilitate formation of soldered connections to circuit conductors.

According to the invention, a very precise electrical end of the resistance element, and permanently stable and extremely low-resistance end connection, are formed and provided by forming a loop or bight of strong highly conductive metal around an end portion of the mandrel and composition, and drawing tightly the bight and securing the same under permanent tension. The loop or bight at least is preferably of flat strip-like form, and for convenience the entire conductive member forming the loop may be of flat strip form. Thus, as is indicated in FIGURES 2 and 3, a flat strip or ribbon-like conductor 22 extends inwardly through the recess in the interior of terminal 20, forms a loop or bight 22b around the inner surface of an end portion of coating 30e and the mandrel 30, and extends outwardly through the terminal 20. The external reaches of the conductor 22 are subjected to considerable tension and thus the bight or loop is brought into permanent and firm physical and electrical contact with the resistive composition adjacent the end of mandrel 30. After tensioning of the bight and adjacent reaches of conductor 22 the external reaches are drawn divergently apart and into contact with the end surface of terminal head 20h and are there held captive, preferably by being welded thereto, with the internal reaches

and bight 22b still under tension. Thereafter, a portion of the recess in the interior of the terminal 20 is filled, or at least partially filled, with molten solder. Upon cooling (from the outside inwardly) the solder 26 shrinks in an outward direction and applies additional tension to the conductor 22 in the upward direction as viewed in FIGURE 3. Thus the terminal is at once sealed, the conductor permanently tensioned with the bight tightly embracing the resistive element 30e, and the conductivity of the electrical path from the element to terminal head 20h increased substantially to bring the resistance of that path to an extremely low and negligible value.

Prior to completion of the resistance-element termination procedures hereinbefore described, the resistive coating forming element proper 30e is removed for at least a short distance back from the end of the core 30 in all instances in which core 30 is an insulated conductor, with care being exercised to leave intact the enamel or like insulation, whereby there is left a gap (denoted by G in FIGURE 2) between the end of the wire core and the end of the resistive coating. Further, following drawing-up or tensioning of conductor 22 about the end portion of the resistance element, a small amount of conductive adhesive may be, and preferably is, applied over that portion of the resistive coating remaining exposed next-adjacent the end of the core, and over the adjacent part of the bight of conductor 22, as indicated at A in FIGURE 2. As is now evident, the tightly-tensioned conductor 22 now defines at E (FIGURE 2) a definite electrical end of the resistance element proper, and also provides an "end-resistance" of substantially zero value for the variable resistor or potentiometer in which the element and terminal are installed. Since the termination structure and mode are or may be the same at the other end of the resistance element (at terminal 22), the same characteristics are or may be evident at both ends of element 30e.

Referring to FIGURE 4, it will be noted that the conductor 22 tightly engages the resistive coating or element 30e along the entire arcuate "width" or transverse section of the element, so there is no narrowing "effect" at the electrical ends of the element, as is the case when only a portion of the element is brought into contact with the terminal conductor. Any such narrowing produces undesirable nonlinear electrical characteristics in prior-art potentiometers, which undesirable feature is prevented by the described structure.

The preceding description of an exemplary variable resistor incorporating a resistance-element termination and procedure therefor has not had reference to certain other of variable resistor components such as the actuating shaft, contact and contact-carrier or slider, and electrical connections between the contact and third terminal 24, since those components and arrangements thereof are conventional and illustrated in the pertinent prior-art patents and per se form no part of the present invention. Further, the preceding description has made evident the attainment of the several objects of the invention. In the light of the disclosure changes and modifications within the true spirit and scope of the invention will occur to those skilled in the art; and hence it is not desired that the invention be restricted to the exact details of the exemplary illustrated structure embodying and utilizing the invention other than as required by the appended claims.

I claim:

1. In a resistor, a resistance element comprising an elongate core and an elongate coating of resistive composition adhering to the core; support means, supporting the said core and coating in a definite position; a terminal member supported in spaced relation to said resistance element by said support means said terminal member having a conductor-receptive recess; and a slender electric conductor extending around and in

electrical contact with a short extent of said coating of resistive composition, said conductor being tensioned and forming a tensioned bight or bend extending around said core and in said bight compressively engaging said short extent of said coating, and end portions of said conductor being secured in recess in said terminal member and conductively connected with said terminal member and said conductor being under tension adjacent said bight, whereby said conductor is maintained in firm compressive electrical contact with said coating and provides an extremely low-resistance electrical end connection to said resistive coating and forms an electrical end for said element.

2. A structure according to claim 1, in which said terminal member is tubular and in which said conductor extends inwardly through the terminal member and around said coating of resistive composition and outwardly through the terminal member, under tension, and in which end portions of said conductor are welded to 15 said terminal member.

3. A structure according to claim 2, in which said tubular terminal member is sealed with solder adherent to said conductor and to the interior of said terminal member whereby said conductor is permanently tensioned and the resistance of the electrical path from said coating of resistive composition to said terminal member is reduced to a negligible value.

4. In a variable resistor having a cylindrical insulation housing with an aperture through a wall thereof and a helical resistance-element core disposed substantially circumferentially around the interior wall surface of said housing:

a hollow terminal member affixed in said aperture and having a passage passing therethrough and communicating with the interior of said housing;

a resistive coating disposed along the interior surface of said resistance-element core and forming an elongate resistive element; and

a thin flat highly-conductive strip having end portions fusion-united to said terminal member outside of said passage and having two reaches extending through said passage and a bight extending around and in electrical contact with an end portion of said resistive coating to provide a termination for the latter, said bight and reaches of said strip being held 45 under applied tension.

5. A variable resistor according to claim 4, in which the said passage of said terminal is sealed with solder, whereby to add to the tension in said bight of said strip and to reduce the resistance of the electrical path from said coating to said terminal member to a negligible value.

6. In a variable resistor having an elongate curved resistance element structure comprising a core of round cross-section and having an insulated surface and said structure further having an elongate coating of resistive material thereon providing a resistance element proper for the variable resistor:

a resistance-element termination device providing an electrical end for said resistance element proper, said termination device comprising an elongate electrical conductor drawn under tension with a bight over said resistance element proper and in electrical contact with the latter,

and means including a rigid metal terminal having a recess therein, in which recess end portions of said conductor are fusion-united to said metal terminal under tension, whereby said bight is held under tension securely embracing said resistance element proper transversely latter to provide a definite electrical end for said resistance element proper and whereby an electrical termination of negligible resistance is provided for said resistance element structure.

7. A combination according to claim 6, in which said means includes supporting means holding said metal terminal spaced from said resistance element structure, and in which reaches of said conductor between said bight and said terminal are maintained under tension by solder fusion-united with said conductor and with said terminal.

8. A variable resistor comprising:

first means, including a generally cylindrical housing with end closures, said housing having at least one aperture through the wall thereof between said end closures;

second means, including a curved resistance-element core disposed around the curved interior wall surface of said housing, and said second means further including an elongate resistive coating disposed at least along a portion of an interior exposed surface of said core to provide an elongate resistance element proper for said variable resistor;

third means, including a metal terminal member mounted in said aperture, extending in part to the exterior of said housing for facilitating electrical connection thereto; and

fourth means, including an elongate slender electrical conductor having first and second ends and an intermediate bight, said bight being disposed under tension transversely across and in electrical contact with a portion of said resistive coating, said conductor having reaches thereof between said bight and said ends held under tension and fusion-united to said terminal member.

9. A variable resistor according to claim 8, said conductor being of the form of a slender flat strip, and said terminal member being of tubular form and in which resistor said conductor is fusion-united to said terminal member by solder disposed in the tubular portion of the terminal member.

10. A method of providing a stable very-low-resistance termination for an elongate curved composition resistance element proper, said method including as steps the following:

disposing an extent of the resistive composition transversely of and facing away from the adjacent end of an elongate recessed terminal provided in fixed position extending away from the resistance element proper;

providing and passing a bight of a bare highly conductive member around and transversely across said element proper and drawing end portions through the recessed terminal member;

drawing taut the bight and reaches of said conductor in the recess of said terminal member to force the bight of the conductor into compressive electrical contact with said resistance element proper; and

fusion-uniting tensioned end portions of said conductor to said terminal member to provide a very-low-resistance electrical path from said element proper to said terminal member.

11. A method according to claim 10, including in said fusion-uniting step, the sub-steps of first spot-welding each end portion of said conductor to the terminal while the conductor is tensioned, and thereafter filling the recess of the terminal with molten solder and causing the solder to chill and solidify in progression toward the resistance element so as to increase the tension in the conductor.
